Primary Examiner — Rhea Shields(74) *Attorney, Agent, or Firm* — Sughrue Mion, PLLC(57) **CLAIM**

The ornamental design for a junction box, as shown and described.

DESCRIPTION

FIG. 1 is a front elevation view of the junction box that we consider to be our invention;

FIG. 2 is a top view thereof;

FIG. 3 is a bottom view thereof;

FIG. 4 is a left side view thereof;

FIG. 5 is a right side view thereof;

FIG. 6 is a rear elevation view thereof; and,

FIG. 7 is a perspective view thereof.

In the drawings, the broken lines are for the purpose of illustrating portions of the Junction Box that forms no part of the claimed design.

1 Claim, 7 Drawing Sheets(56)
